JOHN B. KILBURN AND EDWARD G. BUDD, OF PHILADELPHIA, PENNSYLVANIA, ASSIGNORS TO THE HALE AND KILBURN MANUFACTURING COMPANY, OF PHILADELPHIA, PENNSYLVANIA, A CORPORATION OF PENNSYLVANIA.

UPPER BERTH FOR SLEEPING-CARS.

No. 922,913.

Specification of Letters Patent.

Patented May 25, 1909.

Application filed May 27, 1908. Serial No. 435,220.

To all whom it may concern:

Be it known that we, JOHN B. KILBURN and EDWARD G. BUDD, both citizens of the United States, and residing at Philadelphia, 5 in the county of Philadelphia and State of Pennsylvania, have invented a certain new and useful Improvement in Upper Berths for Sleeping-Cars, of which the following is a specification.

10 This invention relates to sleeping-cars and has reference particularly to the construction of the upper berths of such cars.

The object of the invention is to provide an improved construction of upper berth, the 15 improvements being directed to making such a berth more comfortable by making the upper surface thereof more yielding, and to so constructing the berth as to facilitate the operation of cleaning.

20 The construction of the upper berths of sleeping-cars heretofore employed has been open to serious objection on the ground that the beds thus provided have not been sufficiently soft and comfortable, and this has 25 been due to the fact that the springs for supporting the yielding surface of the bed have not been made of sufficient length because of the limitation imposed upon the total thickness of the berth in view of the limited space 30 which it may occupy within the car.

One object of our invention is to overcome this objection, and we have found that this may be done by so constructing the berth as to utilize practically all of the thickness of 35 the berth in the length of the springs for supporting the yielding surface of the bed. For this purpose the springs are extended at their lower ends all the way down to the panel of the berth and the latter is preferably made 40 of sheet-metal, since by thus decreasing its thickness the length of the springs may be correspondingly increased. When so constructed, the surface of the bed is so yielding supported as to make it quite comfortable, even though the total thickness of 45 the berth remains unchanged.

Another object of the invention is to provide a berth in which the mattress is made of a plurality of sections, any one of which may 50 be taken out, cleaned and replaced independently of the other sections. In the upper berths as heretofore constructed, considerable difficulty has been experienced in properly cleaning the berth, because of the

great inconvenience in taking out a single-piece mattress. The improved construction offers the further advantage that the several sections of a mattress may be differently arranged, when replaced, so that they will wear evenly.

60 The preferred embodiment of our invention is illustrated in the accompanying drawings, in which—

Figure 1 is a plan view of the berth broken away and sectioned in part; Fig. 2 is a transverse section through the mattress, on line 2—2 of Fig. 1; Fig. 3 is a view in section on line 3—3 of Fig. 2; Fig. 4 is a transverse section of a wooden-frame berth; Fig. 5 is a section on line 5—5 of Fig. 4, showing the sections of the mattress in elevation; and Fig. 6 is a central section of a modified form of berth.

Referring first to Fig. 6, 1 indicates the side wall of a car on which the berth is pivotally mounted, the side-frames 2 of the berth being provided with trunnions 3 which are received in bearings secured upon the wall of the car.

In Fig. 4, a wooden-frame berth is shown, this consisting of side-frames 4 and 5 connected at their ends by wooden end-members 6 and a wooden panel 7, which is secured within this rectangular frame. Mounted upon the panel 7 and the frame of the berth, are a plurality of spiral springs 8, arranged 80 in rows lengthwise and crosswise of the berth. The lower ends of these springs may be tied together by thin sheet-metal strips, as indicated at 9, and the upper ends of the springs of each row may be similarly secured to thin 85 sheet-metal strips 10. A webbing 11 may be inserted between the ends of the springs and the strips to which they are fixed, to prevent noise due to the rattling of the metallic surfaces one on another. Thin, flat, sheet- 90 metal springs 12 may be provided extending across the cushion, each overlying a line of the spiral springs, and each secured to the strips 10 overlying the same. These flat springs support a fabric 13, which overlies 95 them and the edges of which are secured in any suitable manner at the bottom of the mattress. It will be seen that by this construction the spiral springs 8 are almost equal in length to the total thickness of the berth, 100 since the lower ends of these springs extend all the way down to the wooden panel 7 and bear thereon except where they extend over

the thin strips 9. By reason of the great length of the springs 8, the surface of the berth is more yieldingly supported than the surface of a berth constructed as has heretofore been the practice, and the berth will therefore be much more comfortable than those heretofore provided. In pivotally mounted berths of this character, it is usual to employ a lock at the center of the upper edge of the berth, operating reciprocating rods, the ends of which are connected to latches at the ends of the berth, adapted to enter openings in the structure of the car at the ends of the berth. In order to inclose and position these rods and latches, a strip of sheet-metal 14 is provided, secured at its edges to the side-member 5 and the panel 7 and bent intermediate its lateral edges so as to provide between it and the panel 7 a space in which the rods and latches may be received and in which they may move as the lock is operated.

In order to secure even greater length for the springs 8, the panel 7 may be made of sheet-metal, thereby permitting of increasing the length of the springs 8 by the difference between the thickness of the sheet-metal and wooden panels. Such a construction is shown in Fig. 6. In this form of berth, the end-members 2 of the frame of the berth are metallic castings curved in the direction of their length and of angular cross-section. The side-members 15 of the frame are also metallic pieces of angular cross-section and are secured at their ends to the end-members 2. To the frame thus constructed, is secured a panel 16 of thin sheet-metal, this panel being flanged at its edges as shown in Fig. 6 and secured to the members of the frame by means of rivets, which enter the sides of the frame-members rather than the lower faces thereof, so as not to show when the berth is closed. A strip 14 of sheet-metal may be secured at its lateral edges to the upper side-member 15 and to the panel 16, to provide a guideway for the locking members as above described. The mattress may be constructed as described above in connection with Fig. 4. It will be seen that by this construction the springs 8 for supporting the yielding surface of the mattress are of even greater length than the springs shown in Fig. 4, and the bed will have the maximum softness permitted by the thickness of the berth.

The mattress for the berth is constructed in a plurality of sections arranged to lie side by side within the frame of the berth, as in this way the several sections may be readily taken out for the purpose of repairing or cleaning, and may be arranged within the berth in different relations, so that the wear thereon will be evenly distributed. In Fig. 5, we have shown two mattress sections, 17, supported upon the wooden panel 7 within

the frame of the berth. As the strain upon the panel 7, due to the weight supported thereby when the sections of the mattress are thus arranged, might be so great as to cause cracking of the wood, we prefer to employ a brace 18 between adjacent sections of the mattress, this brace consisting of a strip of metal of T section, extending across the berth and secured at a number of points to the panel 7. In a berth employing a sheet-metal panel, as shown in Fig. 6, such a brace need not be employed.

Referring now to Figs. 1, 2 and 3, the construction of mattress which we prefer to employ will be described. The mattress has an upper and a lower rectangular frame, each consisting of four strips of sheet-metal secured together at their ends, the lower frame being indicated by the reference 19 and the upper one by the reference 19'. Extending across the cushion between the side-members of the lower frame 19, are a plurality of strips 20 of thin sheet-metal, having their ends secured by rivets to the side-members of the lower frame 19. A plurality of narrow sheet-metal strips 21 extend lengthwise of the mattress between the end-members of the lower frame 19 and are secured intermediate their ends to the strips 20 and at their ends to the end-members of the lower frame 19. The springs 8 are secured at their lower ends to the strips 20 and 21, by means of staples or rivets or other suitable means, a strip of coarse fabric 22 being laid over each strip 20 and between it and the lower ends of the springs 8 supported thereon, as shown in Fig. 2. The upper ends of the springs 8 may be secured to thin strips of sheet-metal 23 running lengthwise of the mattress and secured at their ends to the end-members of the upper frame 19', and these strips 23 or the upper ends of the springs 8, or both, may be secured to flat sheet-metal springs 24 extending across the mattress and secured at their ends to the side-members of the upper frame 19'. Each flat spring 24 may be covered with a strip of coarse fabric 25. A covering 26 of coarse fabric is laid over the entire upper surface of the mattress, and its edges are carried down to the bottom of the mattress and secured thereto in any suitable manner. An outer covering 27 of ticking or other suitable fabric is laid over this coarse covering 26, and its edges are also carried down to the bottom of the mattress. A covering of fabric is provided for each of the strips of the lower frame 19, and the coverings 26 and 27 may be secured in position by sewing the edges thereof to this covering for the strips of frame 19. Or, as shown in Fig. 2, the outer covering 27 may have the edge portions thereof carried down and around the strips of the lower frame 19, and the edges of the coarse covering 26 may be sewed to the covering 27 at 28; the construction in this respect, how-

ever, may be changed as desired. As thus constructed, the bottom of the mattress is open between the several strips 20, so that the interior of the mattress may be cleaned.

- 5 If desired, however, the outer covering 27 may be extended over the bottom of the mattress or a separate covering may be provided for the bottom of the mattress; in either case, this bottom covering is arranged 10 to be detachable, as by sewing it along one edge and providing buttons for holding the other three edges.

In Fig. 1, which shows the mattress constructed as above described and arranged 15 upon a metallic-panel berth of the type illustrated in Fig. 6, the mattress is shown as consisting of two mattress sections arranged side by side. As thus constructed, either section of the mattress may be readily taken 20 out, in order to clean or repair it, and in replacing the sections within the frame of the berth they may be differently arranged, so that the wear thereon will be uniform.

It will be seen that in a mattress constructed as above described, the lower ends 25 of the spiral springs for supporting the yielding surface of the mattress bear directly upon the upper surface of the panel of the berth so that these springs are of the maximum thickness permitted by the thickness of the berth. In order to position the springs, strips of thin 30 sheet-metal are employed to which the lower ends of the springs are affixed and the springs extend over these but bear on the panel on either side of the strips; instead of the sheet-metal strips, other means might be employed for tying the lower ends of the springs together to position them.

Having now described our invention, what 40 we claim as new therein and desire to secure by Letters Patent is as follows:—

1. In a sleeping-car, a side-wall, a frame for a berth pivotally mounted thereon, a panel secured to said frame, and a mattress 45 supported on said frame and provided with a spring-supported upper surface, the lower ends of said springs of the mattress extending in close proximity to said panel, substantially as set forth.

50 2. In a sleeping-car, a side-wall, a frame for a berth pivotally mounted thereon, a panel secured to said frame, and a mattress having strips extending across the frame and spiral springs secured to said strips and 55 yieldingly supporting the upper surface of the mattress, said strips being adapted to bear upon the upper surface of said panel, substantially as set forth.

3. In a sleeping-car, a side-wall, a rectangular frame for a berth pivotally mounted thereon, a panel secured to said frame, and a mattress supported on said frame and provided with sheet-metal strips extending across the bottom thereof and spiral springs 65 mounted on said strips and yieldingly sup-

porting the upper surface of the mattress, said strips being adapted to bear on said panel and the lower ends of said spiral springs being spaced apart from said panel only by said strips, substantially as set forth. 70

4. In a sleeping-car, a side-wall, a frame for a berth pivotally mounted thereon, a panel of sheet-metal secured to said frame, and a mattress supported on said frame and provided with a spring-supported upper surface, the lower ends of the springs of the mattress extending in close proximity to said sheet-metal panel, substantially as set forth. 75

5. In a sleeping-car, a side-wall, a frame for a berth pivotally mounted thereon, a panel of sheet-metal secured to said frame, and a mattress supported on the frame and provided with sheet-metal strips extending across the bottom thereof and spiral springs mounted on said strips and yieldingly supporting the upper surface of the mattress, said strips being adapted to bear on said sheet-metal panel and the lower ends of said spiral springs being spaced apart from said panel only by said strips, substantially as set 80 forth. 85

6. In a sleeping-car, a side-wall, a frame for a berth pivotally mounted thereon, a panel secured to said frame and a mattress supported by the frame, said mattress having sheet-metal strips running lengthwise thereof at its side edges, sheet-metal strips extending across the mattress, secured at their ends to said strips and corresponding in shape to said panel, spiral springs mounted 95 upon said last-named strips and having their lower ends in proximity to said panel, and a surface covering for the mattress yieldingly supported by said springs, substantially as 100 set forth. 105

7. In a sleeping-car, a side-wall, a rectangular frame for a berth pivotally mounted thereon, a panel of sheet-steel secured at its lateral edges to said frame, and a mattress supported by said frame, said mattress having sheet-metal strips running lengthwise thereof at its side edges, sheet-metal strips extending across the mattress, secured at their ends to said strips and corresponding in shape to said panel, spiral springs mounted 110 on said last-named strips and having their lower ends in proximity to said panel, and a surface covering for the mattress yieldingly supported by said spiral springs, substantially as set forth. 115

8. In a sleeping-car, a side-wall, a rectangular frame for a berth pivotally mounted thereon, a sheet-metal panel secured to the frame, and a mattress supported by the frame, said mattress having a rectangular 125 frame, sheet-metal strips extending between the side- and end-members of the frame of the mattress, secured at their ends to said members and corresponding in shape to the panel underlying them, spiral springs secured 130

- to said strips, and a covering for the mattress yieldingly supported by said springs and secured at its edges to the frame of the mattress, substantially as set forth.
- 5 9. In a sleeping-car, a side-wall, a rectangular frame for a berth pivotally mounted thereon, a sheet-metal panel secured to the frame, and a mattress supported by the frame, said mattress having an upper and 10 a lower rectangular metallic frame, sheet-metal strips extending across the lower frame, secured at their ends thereto and shaped to correspond to the panel underlying them, flat sheet-metal springs extending 15 across the upper frame and secured at their ends thereto, spiral springs secured to said strips and said flat springs, and a covering for the mattress yieldingly supported by said spiral springs, substantially as set forth.
- 20 10. In a sleeping-car, a side-wall, a rectangular frame for a berth pivotally mounted thereon, a panel secured to the frame, and a mattress supported by the frame, said mattress consisting of a plurality of mattress 25 sections individually removable and interchangeable as to their positions upon the berth frame, substantially as set forth.
11. In a sleeping-car, a side-wall, a rectangular frame for a berth pivotally mounted 30 thereon, a sheet-metal panel having its lateral edges secured to said frame, and a mattress supported by said frame, said mattress consisting of a plurality of mattress sections individually removable and interchangeable 35 as to their positions upon the berth frame, substantially as set forth.
12. In a sleeping-car, a side-wall, a rectangular frame for a berth pivotally mounted 40 thereon, a panel secured to the frame, and a mattress supported by the frame, said mattress consisting of a plurality of mattress sections individually removable and interchangeable as to their positions upon the 45 berth frame, and a brace extending across the panel and secured thereto between each pair of adjacent mattress sections, substantially as set forth.
13. In a sleeping-car, a side-wall, a frame 50 for a berth pivotally mounted thereon, a panel secured to said frame, and a mattress
- supported on said frame and provided with springs for supporting the upper surface thereof, the lower ends of said springs for the mattress bearing upon said panel, substantially as set forth. 55
14. In a sleeping-car, a side wall, a frame for a berth pivotally mounted thereon, a panel secured to said frame, and a mattress supported on said frame and provided with springs for supporting the upper surface 60 thereof, the lower ends of said springs for the mattress bearing upon said panel, and means for positioning the lower ends of the springs. 65
15. In a sleeping-car, a side-wall, a frame for a berth pivotally mounted thereon, a panel secured to said frame and a mattress supported on said frame and provided with springs for supporting the upper surface thereof, the lower ends of said springs for the mattress bearing upon said panel, and means 70 for positioning the lower ends of the springs, substantially as set forth. 75
16. In a sleeping-car, a side-wall, a frame for a berth pivotally mounted thereon, a panel secured to said frame, and a mattress supported on said frame and provided with a frame, flat sheet-metal springs extending across the same and spiral springs supporting said flat springs, the lower ends of said spiral 80 springs bearing on said panel, substantially as set forth. 85
17. In a sleeping-car, a side-wall, a frame for a berth pivotally mounted thereon, a panel secured to said frame, and a mattress supported on said frame and provided with a frame, flat sheet-metal springs extending across the same and spiral springs supporting said flat springs, the lower ends of said spiral 90 springs bearing on said panel, and means for positioning the lower ends of the spiral springs, substantially as set forth. 95
